FIRECRACKER PISTOL

Selma G. Anthony, Wilson, Tex.

Application May 17, 1937, Serial No. 143,171

1 Claim. (Cl. 124—26)

This invention relates to firecracker pistols, and has for one of its objects the production of a simple and efficient toy pistol which is so constructed as to throw a lighted firecracker with a fair degree of accuracy when discharged or ejected from the pistol.

A further object of this invention is the production of a firecracker pistol for lighting the fuse of a firecracker and then forcibly ejecting the lighted firecracker by drawing the firecracker longitudinally of a trackway formed of parallel rods arranged in transverse triangular relation spaced at a proper distance to hold the firecracker upon the trackway and allow the firecracker to freely slide thereon.

Other objects and advantages of this invention will appear throughout the following specification and claim.

In the drawing:

20 Figure 1 is a side elevation partly in section illustrating my improved firecracker pistol;

Figure 2 is a longitudinal sectional view taken on line 2—2 of Figure 1, certain parts being shown in elevation;

25 Figure 3 is a vertical sectional view taken on line 3—3 of Figure 1;

Figure 4 is a horizontal sectional view taken on line 4—4 of Figure 1;

Figure 5 is a longitudinal sectional view 30 through the ejector casing illustrating the ejector and ejecting spring;

Figure 6 is a vertical sectional view taken on line 6—6 of Figure 1;

Figure 7 is a vertical sectional view taken on 35 line 7—7 of Figure 1;

Figure 8 is a vertical sectional view taken on line 8—8 of Figure 1;

Figure 9 is a sectional perspective view of a portion of the ejector casing showing the mounting of the ejector therein;

Figure 10 is a fragmentary perspective view of a portion of the trackway through which the firecracker is adapted to slide while being forcibly ejected.

45 By referring to the drawing it will be seen that 15 designates the handle or grip portion of the pistol or gun which is provided with a conventional trigger guard 16 and this handle or grip portion 15 carries a projecting tubular ejector casing 17 extending forwardly of the handle or grip portion 15, as shown in Figure 1. This ejector casing 17 is provided with a longitudinally extending slot 18 along the bottom portion thereof near its inner end through which extends 50 a finger-piece 19 carried by the bottom portion of the ejector 20. The ejector 20 preferably comprises a rectangular hollow casing formed of metal or other suitable material and is mounted to slide on the parallel longitudinally extending 55 track rods 21 which are mounted within the

ejector casing 17, the forward ends of the track rods 21 being secured to the end wall 22 of the ejector casing 17 and the rear ends of these track rods 21 being secured to the partition disc 23 carried near the rear end of the ejector casing 17. This ejector 20 is adapted to freely slide upon the track rods 21 both while it is being set or cocked and while it is ejecting the firecracker, as will be hereinafter described.

A tension coil spring 24 is mounted within the 10 ejector casing 17 and one end of this tension coil spring 24 is secured, as at 25, to the forward end of the ejector 20 by being extended through the aperture 26. The opposite or forward end of the 15 coil spring 24 is connected to the eye 27 of the 20 rod 28, which rod 28 is provided with a finger loop 29 at its outer end whereby the rod 28 may be moved longitudinally through the end wall 22 of the casing 17 and a pin 30 extended through a suitable aperture in the rod 28 to hold the rod 28 25 in a set position to increase the tension of the spring 24 should it be desired, in this way increasing or decreasing the range of the pistol by adjusting the tension of the coil spring 24. Any suitable or desired means might be employed for 30 adjusting the tension of the coil spring 24 without departing from the spirit of the invention. The coil spring 24 is mounted so as to surround the track rods 21 and is of sufficient size to expand and contract without interference with the track 35 rods 21 as will be obvious by considering the drawing. The ejector 20 is provided with an ejector tongue formed of spring metal and indicated by the numeral 31 which ejector tongue extends rearwardly of the ejector 20 as shown in 40 Figures 1 and 9, and extends through a slot 17a formed in the top of the casing 17, the tongue 31 having an upwardly extending spur 32 which is adapted to engage the firecracker F. The ejector tongue 31 is provided with an upwardly extending 45 knob 31a near the upwardly extending spur 32 which is adapted to engage the depressed portion 17a of the casing 17 which is located near the forward end of the slot 17a in which the spur 32 travels. This will cause the ejector tongue 31 to be depressed to the position shown in Figure 5 while the gun is being loaded and the firecracker F is being placed in position and hold the spur 32 out of the path of the movement of the firecracker F during the process of loading. As the 50 gun is cocked, and the ejector 20 is moved rearwardly, the tongue 31 will snap up to its normal position shown in Figure 1 for engagement with the firecracker. The ejector 20 is also provided with a rigid cocking bar 34, the bar 34 projecting 55 rearwardly of the ejector 20 and having a notch 35 formed in its under face and an inclined bottom wall 36 adjacent the notch 35.

A trigger 37 is pivotally secured to a spring latch 38, which latch is anchored, as at 39, with- 60

in the inner end of the casing 17 adjacent the hand or grip portion 15. The spring latch 38 is provided with an upstanding tongue 40 at its outer free end for engaging the notch 35 of the cocking bar 34. By considering Figure 1, it will be seen that by pulling the trigger 37 toward the grip portion 15, the upper end of the trigger 37 will ride upon the lower inclined face 36 of the cocking bar 34 and draw the tongue 40 out of engagement with the notch 35 releasing the ejector 20 from the spring latch 38, and in this way allowing the spring 24 to pull the ejector 20 longitudinally of the casing 17.

15 As shown in the drawing, it will be seen that directly above and extending longitudinally of the casing 17 is a projectile trackway T consisting of three longitudinally extending track rods 41 which are held in definite spaced triangular relation by means of the bands 42 which are welded or fixed in any suitable or desired manner to the track rods 41, these bands 42 being preferably slidable upon a resilient track strip 44 carried by the upper face of the casing 17 and secured thereto in any suitable manner, such for instance as that shown in Figure 5. The bands 42 are provided with depressed loop portions 43b which may freely slide longitudinally of the resilient track strip 44. A depressed latch 44a is formed near one end of the strip 44 behind which the rear band 42 is adapted to fit to hold the projectile trackway T in a set or firing position. When it is desired to place the firecracker F within the trackway T the trackway T is moved forwardly in the direction of the arrow indicated in Figure 1 and the depressed latch 44a will allow the rear band 42 to pass forwardly due to the fact that the track strip 44 is of resilient material. When the firecracker 46 F has been placed in position, the trackway T may be pulled back to the position shown in Figure 1 and the latch 44a will hold the trackway in this set position. The rear band 42a is cut away, as at 43, to allow the ejector tongue 31 to slide longitudinally of the trackway T.

As shown clearly in Figure 7, the track rods 41 are arranged in triangular relation with respect to each other in a manner whereby the sides of the triangle formed will be of less diameter than the diameter of the cross section of the largest firecracker which might be able to slide longitudinally between the triangularly arranged and spaced track rods 41.

The present device may be used with or without a lighting device, but for the purpose of convenience, I preferably employ a lighting device 45 of any suitable or desired type, such for instance as the conventional cigarette lighter having a burner 46, a flint 47, and sparking wheel 48 located directly in the rear of the firecracker F when placed in a firing position and in a position where the fuse 49 of the firecracker F will overlie the burner 46.

A hood 50 is hinged, as at 51, at one side at the top of the grip portion 15 and above the lighting device 45 so as to shield the fuse 49 and burner 46, the rear end of the hood 50 being open. This hood 50 may be swung to the position shown in dotted lines in Figure 6 when loading or unloading the gun or pistol.

70 The tension of the throwing spring 24 may be varied according to the length of the fuse, and thus prevent the duplication of firecrackers that would fit the gun. In other words, fire-

crackers having a proper length of fuse only could be used in the gun.

The operation of the device is as follows:—

The firecracker F is placed within the trackway T which constitutes a barrel by inserting 5 the firecracker at the inner end, the hood 50 first being thrown to the position shown in dotted lines in Figure 6. The firecracker F may be easily slid within the trackway T over the ejector tongue 31 due to the inclined face 33 thereof, and as soon as the firecracker has been placed in position the ejector tongue 31 will snap into 10 engaging position such as is shown in Figure 1. The hood 50 is then thrown to the position as shown in full lines in Figure 6, and as also shown 15 in Figure 1, and the fuse 49 is lighted through the medium of a piece of punk or by means of a lighter 45, and the trigger 37 is then pulled for releasing the tongue 40 from the notch 35. The tension spring 24 will then suddenly pull 20 the ejector 20 longitudinally of the ejector casing 17 and drive the firecracker F longitudinally through the trackway T, enabling the operator to direct the fire of the pistol in a desired direction and with a reasonable amount of accuracy. 25 The tension of the spring 24 may be adjusted, as previously described, depending upon the desire, to regulate the distance of throw of the firecracker F. The track rods 41 will provide a smooth running face or surface at three contacting points throughout the length of the firecracker as it travels longitudinally of the trackway T and at the same time will provide an open barrel within which the firecracker would not be confined in the event of the accidental 30 explosion of the firecracker before it is ejected from the trackway T. Because of the instant discharge or ejection of the firecracker from the trackway T by the release of the trigger 37, the operator may cause the firecracker F to be 35 immediately discharged, as soon as the fuse 49 is lighted, and as a matter of fact, explode the firecracker with greater safety than is now the common practice of lighting and then manually throwing the firecracker. As soon as the trigger 40 45 is pulled, the ejector 20 will automatically eject the firecracker F through the trackway T, the ejector 20 sliding freely upon the track rods 24 previously described. The ejector 20 is cocked or set by pulling upon the finger-piece 19 and moving the ejector 20 rearwardly until the tongue 49 of the spring latch 38 engages the notch 35.

Having described the invention, what I claim as new is:—

A pistol of the class described comprising a 55 body, a barrel extending longitudinally thereof, the barrel comprising a plurality of longitudinally extending track rods arranged in spaced transverse triangular relation, the track rods constituting a longitudinal firecracker-engaging 60 means whereby a firecracker may slide longitudinally of the trackway, means for automatically 65 ejecting and moving a firecracker longitudinally of the trackway, reinforcing bands engaging the outer faces of the track rods and holding the track rods in definite spaced relation, a resilient track strip engaging said reinforcing bands for holding the same in engagement with said body and permitting said trackway to move longitudinally of the body, and said 70 resilient track strip having means for engaging one band for holding said trackway in a set and firing position.
